J. D. PEDERSEN.

FIREARM.

APPLICATION FILED DEC. 11, 1919.

1,395,291.

Patented Nov. 1, 1921.

Inventor:

John D. Pedersen,
By his Atty, J. F. Richards.

UNITED STATES PATENT OFFICE.

JOHN D. PEDERSEN, OF JACKSON, WYOMING.

FIREARM.

1,395,291.

Specification of Letters Patent. Patented Nov. 1, 1921.

Original application filed July 30, 1915, Serial No. 42,774. Renewed July 17, 1919, Serial No. 311,689. Divided and this application filed December 11, 1919, Serial No. 344,027.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

This invention relates more especially to that class of firearms, which is usually 10 designated as small arms, and a principal object of the invention is to furnish an improved firing mechanism and grip-safety device particularly applicable to auto-loading and automatic pistols.

15 One class of small arms to which my present improvements are applicable, includes the auto-loading pistols having a frame or receiver, and a grip-stock, or handle portion, which is adapted to receive 20 a firing mechanism and a safety device which is operable by hand grip or compression.

An improved auto-loading pistol of this kind is described in my Patent No. 1,348,733, 25 dated August 3, 1920, and granted on my co-pending application (renewal) Serial No. 311,689, filed July 17th, 1919, and the improvements herein described and claimed are also illustrated in my said patent, but 30 are not specifically claimed therein. Therefore for convenience of illustration, I have herein shown my present improvements as arranged and applied to the particular kind of auto-loading pistol which is illustrated 35 in the drawings of said patent, to which reference may be had, and which pistol is provided with a sliding breech action.

A feature of my firing mechanism and grip-safety device is that it is a firing mechanism and grip-safety device arranged to prevent discharge of the firearm by locking 40 the firing-member or hammer and the sear-member of the firing mechanism in firing position, and also locking the sliding breech 45 action of the firearm to prevent effective contact between the firing-pin and cartridge.

Another feature of my invention is that the firing mechanism comprises a firing-member or hammer which has a relatively

sliding movement instead of an oscillating 50 movement, and which firing member or hammer does not contact directly with the firing-pin, but engages or actuates a lever which contacts with the firing-pin of the firearm.

55 Another feature of my invention is that it is provided with what I term a resisting and retracting member which is arranged adjacent to the sear member of the firing mechanism, one purpose of which is to move 60 downward or retract a slidale member or controller when the firing-member or hammer is moved from firing position to fired position, which slidale member or controller is in upward position when the firing-member or hammer is in firing position and thus locks the sliding breech action of the firearm, the slidale member or controller being held in such upward or locking position by the grip-safety portion of my invention; and a second purpose of such resisting and retracting member is to engage 65 said slidale member or controller and at the same time to engage said firing-member or hammer, when the slidale member or controller is in such upward or locking position, and thereby to resist or prevent movement of the firing-member or hammer from 70 firing position to fired position.

In the accompanying drawings, which 75 illustrate an embodiment of my firing mechanism and grip-safety device:

Figure 1, is a side elevation, partly broken away, of a pistol provided with my firing mechanism and grip-safety device, 80 showing the firing mechanism of my invention in firing position and the grip-safety portion in normal or safety position, the sliding breech action of the firearm, firing-member or hammer and the sear-member 85 being locked, and the slidale member or controller being in upward or locking position.

Fig. 2, is a fragmentary side elevation, on a larger scale than Fig. 1, partly broken 90 away, showing the firing mechanism of my invention in fired position, and the grip-safety device portion in compressed or un-

locking position, the sliding breech action of the firearm, firing-member or hammer and the sear-member being unlocked, and the slidable member or controller being in down-
ward or unlocking position.

Fig. 3, is a sectional plan view on the line 3—3 of Fig. 2, looking in the direction of the arrow.

Fig. 4, is a view in vertical section on the line 4—4 of Fig. 2, looking in the direction of the arrow, the grip-safety member and firing-member or hammer being removed.

My firing mechanism and grip-safety device comprises a firing-member or hammer H², Figs. 1 and 2, the frame or receiver B and the grip-stock of the firearm being suitably bored or otherwise cut away to receive the firing-member or hammer H² and the various parts of my invention. The firing-member or hammer H² is in form substantially an enlarged rod actuated at its lower end by a firing spring 8^e as hereinafter more particularly described. The firing-member or hammer H² has a substantially vertical motion, and does not have a pivotal or swinging movement properly so called.

The firing-member or hammer H² is guided by a roller 8^p, mounted on the frame or receiver B of the firearm, preferably near the upper end of the firing-member or hammer, the firing member or hammer H² moving vertically between said roller 8^p and a guide face, 8^r, formed in the frame or receiver B of the firearm. The firing-member or hammer H² is provided with a face at 8^s for engaging the end 8^t of an arm 8^t of the lever L², which lever is arranged for actuating the firing-pin P in a manner which will be evident from the drawing. The lever L² is pivotally attached to the sliding breech action of the firearm and is carried thereby, and is provided with an inclined surface at 8^w for operating on the roller 8^p, which roller is fixed to the firing-member or hammer H², so that when the cartridge is fired the rearward movement of the sliding breech action of the firearm under impulse of the discharge of the cartridge will operate to depress the firing-member or hammer H², to its firing or cocked position, Fig. 2. The firing-member or hammer H² is provided on its forward side with a firing-notch or cock-notch 8ⁱ for engaging the sear-notch or face 17^b of the arm S¹¹ of the sear-member S, and provided with a face 8^k for engaging a resisting and retracting member or lever hereinafter described.

The sear-member S, is shown as comprising two arms S^s and S¹¹. The sear-member S is supported on a pin 17^a in the grip-stock of the frame or receiver B of the firearm, the end of the arm S^s of the sear-member S being engageable with the trigger-member F.

A resisting and retracting member or lever S' is pivot-mounted on said pin 17^a,

which member or lever is provided with two arms S¹⁰ and S¹², the purpose of the arm S¹⁰ being to engage or bear upon a face of the slidable member or controller N, hereinafter described, while the arm S¹² engages or bears upon the face or projection 8^k arranged on the firing member or hammer H². The slidable member or controller N, is movable upwardly and downwardly between guide faces 10 and 11, in the frame or receiver B of the firearm.

The slidable member or controller N has at its upper end a point or face 14^a which projects into the path of the sliding breech action of the firearm when the slidable member or controller is in upward position, and thus locks the sliding breech action against rearward movement, and is provided with a shoulder 14^p having an upper surface or face, with which the arm S¹⁰ of the resisting and retracting member S' engages as before stated. The slidable member or controller has an opening 15 therethrough to receive the rear end of a trigger member F, which end fits snugly but freely the opening 15 in such manner as to allow a slight play or movement upward and downward of the trigger-member F therein. The slidable member or controller N has at the lower end of the shoulder 14^p, bottom sides or bottom ends 14^e with which locking-prongs of the grip-safety member hereinafter described engage. The slidable member N is provided with a spring operated actuator 14^m, and is also provided with a lever member n, which is pivotally attached to the slidable member or controller N and which has a face 12 which engages the end of the actuator 14^m, and has a projecting end 13, which engages the adjacent face 17^c of the sear member S, the tendency of the actuator 14^m and the lever member n being to move the slidable member or controller N upwardly, or to locking position, and to move the end of the arm S¹¹ of the sear S toward the firing member or hammer H².

The grip-safety device or portion of my invention generally denoted by G, is insertible in the grip-stock of the firearm, and is engageable at its upper end G² with the frame of the firearm and is provided at its other end with a frame-end g', which is insertible in the grip-stock and attached thereto by a pivot-pin g, to afford compression of the grip-safety member G, preferably in the manner described and set forth in my said patent.

The top portion of the grip-safety member G is slotted out at 7^d to furnish clearance for the hammer H² and the sear-member S, leaving a pair of side-walls 7^e which are extended to a pair of locking-prongs 7^f. These locking prongs or lever-arms are located outside of, and clear of the rear end of the trigger-member F, and when the

grip-safety member G is in its outward or safety position, the locking-prongs 7^t are immediately below the bottom sides or end bottoms 14^c of the slidable member or controller N, which is thereby positively locked against downward movement.

The firing-member H² is provided at its lower end with a ball shaped portion h² which engages or is seated in the cupped portion 10 of the plunger 8^c, which plunger 8^c is movable or slides in a bracket 16 carried by the grip-safety member G and is in sliding contact with the adjacent inner side or face of the grip-safety member G, the plunger 8^c thus engaging the grip-safety member.

The firing spring 8^e as shown is seated in a plug 7^b which is insertible in the frame-end g^c of the grip-safety device G and in the grip-stock. The plunger 8^c provides a movable or sliding abutment for the upper end 20 of the firing-spring 8^e to actuate the firing member or hammer H², and by engagement of the plunger 8^c against the inner side or face of the grip-safety member G' through pressure of the firing spring, retains the end 25 G^c of the grip-safety member in engagement with the frame of the firearm when the grip-safety member is in normal position or position of safety, and returns said member to 30 this position after release of compression of the grip-safety member, the arrangement preferably being that described and set forth in my before mentioned patent.

The trigger member F is movable forwardly to normal firing position by means 35 not shown, and movable rearwardly by pull thereon to discharge the firearm. The rear end of the trigger-member F is engageable with the arm S^s of the sear member S to 40 push the same inwardly.

My firing mechanism and grip-safety device being in normal position or position of safety, Fig. 1, compression of the grip-safety member G disengages or unlocks the 45 prongs 7^t from the bottom sides or end bottoms 14^c of the shoulder 14^p of the slid- able member or controller N, Fig. 2, and permits the slidable member or controller to move downwardly. Pull on the trigger-member F pushes inwardly the arm S^s of the sear-member S, and disengages the sear-notch 17^b of said arm from the cock-notch 8^j of the firing member or hammer H², and permits upward movement of the firing 50 member or hammer by force of the firing spring 8^e.

Upward movement of the firing member or hammer H² carries upwardly the arm S¹² of the resisting and retracting member 55 or lever S' through engagement of the arm S¹² thereof with the face 8^{k'} of the firing member or hammer, the arm S¹⁰ of the member or lever S' then bearing downwardly on the upper surface of the shoulder 14^p of the 60 slidable member or controller and acting as

a retracting means, to force the latter member downwardly and thereby to release the sliding breech action of the firearm.

The roller 8^r, through upward movement of the firing member or hammer H² is disengaged from the end 8^t of the arm 8^t of the lever L² and forced into engagement with the inclined surface 8^w of said lever, thereby forcibly moving the lever L² into contact with the firing-pin P, Fig. 2, and 70 discharging the firearm. The firing member or hammer H² thus, through action of the spring 8^e, is moved from firing position to fired position, or to position which actuates the lever L² to discharge the firearm. 80

The firing member or hammer H² is re-turned to firing or cocked position by rear- 85 ward movement of the sliding breech action of the firearm, which causes the firing mem- ber or hammer H² to move or be forced downwardly by engagement of the inclined surface 8^w of the lever L² with the roller 8^r, the firing member or hammer H² being guided in such movement by the guide-face 8^{p'} and the roller 8^p, the lever L² thus rid- 90 ing upon the roller 8^r until the firing mem- ber or hammer assumes the position shown in Fig. 1. The firing member or hammer H² is thereby moved downward until the sear-notch of the arm S¹¹ of the sear mem- 95 ber S engages the cock-notch 8^j of the firing member or hammer, and locks the latter in firing or cocked position. Engagement of the end 13 of the lever member n with the face 17^e of the sear member S permits the 100

spring actuator 14^m, through engagement thereof with the face 12 of the lever mem- 105 ber n, to move the slidable member or controller upwardly until the end 14^a thereof lies in the path of the sliding breech action of the firearm. The slidable member or controller N is locked in this position by the engagement therewith of the locking-prongs 7^t of the grip-safety member G, while the resisting and retracting member or lever S', 110 through engagement with the face 8^{k'} of the firing member or hammer H² and engagement with the upper surfaces 14^e of the shoulder 14^p of the slidable member or controller N, acts as a resisting means to prevent upward movement of the firing mem- 115 ber or hammer, or movement of the firing member or hammer from firing position to fired position.

Having thus described my invention, I 120 claim:

1. In a firearm, in combination, a slid- 125 ing breech-action of said firearm and com- prising a firing-pin, a frame of said firearm, a firing-pin actuating member carried by said sliding breech action, a firing member slidably movable to fired position and to firing position, and engageable with said firing-pin actuating member when moved to fired position to actuate the same, and en- 130

- gageable therewith for movement thereby to firing position, sear means engageable with said firing member, slidable means engageable with said sliding breech action, 5 means for moving said slidable means in a direction to lock said sliding breech action and lock said sear means and firing member in firing position, means for moving said slidable means in direction reverse to said 10 first mentioned direction when said firing member is moved to fired position, a grip-compressible member engageable with said frame and engageable with said slidable means when in position of safety, to block the slidable means in said locking position, and by grip-compression releasable from both 15 said engagements, and spring means for slidably moving said firing member to fired position. 20 2. In a firearm, in combination, a sliding breech action of said firearm comprising a firing-pin, a frame of said firearm, a firing-pin actuating member carried by said sliding breech action, a firing member slidably 25 movable to fired position and to firing position, and engageable with said firing-pin actuating member when moved to fired position to actuate the same, and engageable therewith for movement thereby to firing position, 30 sear means engageable with said firing member, slidable means engageable with said sliding breech action, means for moving said slidable means in a direction to lock said sliding breech action, and lock said sear means and firing member in firing position, lever means engaging said slidable means and engaging said firing member for resisting movement of said firing member to fired position when the same is in firing position, 35 and for moving said slidable means in a direction reverse to the first mentioned direction when the firing-member is moved to fired position, a grip-compressible member engageable with said frame and engageable 40 with said slidable means when in position of safety, to block said slidable means in said locking position, and by grip-compression releasable from both said engagements, and spring means for slidably moving said firing member to fired position. 45 3. In a firearm, in combination, a sliding breech action of said firearm comprising a firing-pin, a frame of said firearm comprising a grip-stock, a firing-pin actuating member carried by said sliding breech action, a firing member slidably movable to fired position and to firing position, and engageable with said firing-pin actuating member when moved to fired position to actuate the same, and engageable therewith for movement thereby to firing position, sear means engageable with said firing member, 55 slidable means engageable with said sliding breech action, means for moving said slid- 60 able means in a direction to lock said slid- 65 ing breech action, and lock said sear means and firing member in firing position, a pivotally moving member engaging said slid- 70 able means and engaging said firing member for resisting movement of said firing member to fired position when the same is in firing position, and for moving said slidable means in a direction reverse to said first mentioned direction when the firing member is moved to fired position, a grip-com- 75 pressible member engageable with said frame and engageable with said slidable means when in position of safety to block the slidable means in said locking position, and by grip-compression releasable from both 80 said engagements, spring means for slidably moving said firing member to fired position, and trigger means engageable with said sear means to move the sear means to release said firing member for movement to 85 fired position. 4. In a firearm, in combination, a sliding breech action of said firearm comprising a firing-pin, a frame of said firearm, a firing-pin actuator carried by said sliding breech 90 action, a firing member slidably movable to fired position and to firing position, and engageable with said firing-pin actuator when moved to fired position to actuate the same, and engageable with said firing-pin 95 actuator for movement thereby to firing position, a sear member engageable with said firing member, a slidable controller engageable with said sliding breech action when in upward position, and provided with an actuator, a lever member pivotally attached to 100 said controller and engaging said sear member and engaging said actuator to move said controller upwardly when said firing member is moved to firing position to lock said 105 sliding breech action, and lock said sear member and firing member in firing position, a pivotally moving member engaging said firing member and engaging said controller to move the controller downwardly 110 when said firing member is moved to fired position, a grip-operable member engageable with said frame and engageable with said controller when in position of safety, to block said controller in upward position, 115 and releasable by grip-compression from both said engagements, a spring for actuating said firing member, and permitting grip-compression of said grip-operable member, and for returning said grip-operable member to position of safety after grip-compression, and a trigger member engageable with 120 said sear member to release the sear member from engagement with said firing member for movement thereof to fired position. 5. In a firearm, in combination, a sliding breech action of said firearm comprising a firing-pin, a frame of said firearm, a firing-pin actuator carried by said sliding breech 125 action, a firing member slidably movable to 130

- fired position and to firing position, and engageable with said firing-pin actuator when moved to fired position to actuate the same, and engageable with said firing-pin actuator 5 for movement thereby to firing position, a sear member engageable with said firing member, a slidable controller engageable with said sliding breech action when in upward position, and provided with 10 an actuator, a lever member pivotally attached to said controller and engaging said actuator of the controller and engaging said sear member to move said controller upwardly when said firing-member is moved 15 to firing position, a resisting and retracting member engaging said firing member and engaging said controller to resist movement of said firing member to fired position when said firing member is in firing position, and 20 to move said controller downwardly when said firing member is moved to fired position, a grip-operable member engageable with said frame and engageable with said controller when in position of safety, to 25 block the controller in upward position, and releasable by grip compression from both said engagements, a spring for actuating said firing member, and permitting grip-compression of said grip-operable member, and 30 for returning said grip-operable member to position of safety after grip-compression, and a trigger member engageable with said sear member to release the sear member from engagement with said firing member for 35 movement thereof to fired position.

6. In a firearm, in combination, a sliding breech action of said firearm comprising a firing-pin, a frame of said firearm, a firing-pin actuator carried by said sliding breech 40 action and provided with an inclined face and an engaging end, a firing member slidably movable to fired position and to firing position, and provided with roller means and a face for engaging said inclined face and 45 end of the firing-pin actuator when the firing member is moved to fired position to actuate the firing-pin actuator, and for engaging said inclined face and said end of the firing-pin actuator for movement by 50 said engagement to firing position, means for guiding said firing member in its sliding movement, a sear member engageable with said firing member, a slidable controller engageable with said sliding breech action 55 when in upward position, and provided with an actuator, a lever member pivotally attached to said controller and engaging said actuator of the controller and engaging said sear member to move said controller upwardly when said firing member is moved to 60 firing position, a resisting and retracting member engaging said firing member and engaging said controller to resist movement of said firing member to fired position when 65 the firing member is in firing position, and to move said controller downwardly when said firing member is moved to fired position, a grip-operable member engageable with said frame and engageable with said controller when in position of safety, to 70 block the controller in upward position, and releasable by grip-compression from both said engagements, a spring for actuating said firing member, and affording grip-compression of said grip-operable member, and for 75 returning said grip-operable member to position of safety after grip-compression, and a trigger member engageable with said sear member to release the sear member from engagement with said firing member for movement thereof to fired position.

7. In a firearm, in combination, a sliding breech-action of said firearm comprising a firing-pin, a frame of said firearm comprising a grip-stock, a firing-pin actuator carried by said sliding breech action and provided with an inclined face and an engaging end, a firing hammer slidably movable to fired position and to firing position, and provided with a roller and an end-face for engaging said inclined face and end of the firing-pin actuator when the firing hammer is moved to fired position to actuate the firing-pin actuator, and for engaging said inclined face and end of the firing-pin actuator for movement by said engagement to firing position, and provided with a cock-notch, means for guiding said firing hammer in its sliding movement, a sear member provided with lock means for engaging said cock-notch of the firing member, and provided with a face for engaging a lever member, and provided with an extending end, a slid- 80 able controller engageable with said sliding breech action when in upward position, and provided with a spring operated actuator, a lever member pivotally attached to said controller and engaging said actuator, and engaging said face of the sear member to move said controller upwardly when said firing hammer is moved to firing position, a resisting and retracting member engaging at one end said firing hammer and engaging at its other end said controller to resist movement of said firing hammer to fired position when the firing hammer is in firing position, and to move said controller downwardly when said firing hammer is moved to fired position, a grip-operable member engageable at its upper end with said frame and provided with means for engaging said slidable controller when in position of safety, and releasable by grip-compression from both said engagements, a firing spring connected at its upper end to said firing hammer, sliding means engaging said grip-stock and engaging said grip-operable member, said spring being operatively connected at its lower end to said grip-operable member and abutting said sliding 100

105

115

120

125

130

means, and a trigger member engageable with said extending end of the sear member to release the sear member from engagement with said firing hammer for movement 5 thereof to fired position.

8. In a firearm, in combination, a sliding breech action of said firearm comprising a firing-pin, a frame of said firearm comprising a grip-stock, a firing-pin actuator carried by said sliding breech action and provided with an inclined face and an engaging end, a firing hammer slidably movable to fired position and to firing position, and provided with a roller and an end-face for engaging 10 said inclined face and end of the firing-pin actuator when the firing hammer is moved to fired position, and for engaging said inclined face and end of the firing-pin actuator for movement by said engagement 15 to firing position, and provided with a cock-notch, and provided with a face for engaging a resisting and retracting member, means for guiding said firing hammer in its sliding movement, a sear member provided with 20 a lock-notch for engaging said cock-notch, and provided with a front face, and provided with an extending lower end, a slideable controller provided with an end for engaging said sliding breech action, and provided 25 with a spring operated actuator, and provided with a shoulder having an upper-engaging surface, and provided with a slot for receiving a trigger member, and provided with an end-face, a lever member pivotally attached to said controller provided 30 with a face for engaging said actuator, and provided with an end for engaging said front-face of the sear member, a resisting and retracting member engaging at one end 35 said face of the firing hammer, and engaging at its other end said upper surface of the shoulder of said controller, a grip-safety member provided with a frame-end pivotally attached to the grip-stock, the grip-safety member being engageable at its upper 40 end with said frame of the firearm and provided at its lower end with locking-prongs for engaging said end-face of the controller when in position of safety, and releasable 45 from engagement with said frame of the fire-arm and controller by grip-compression, a firing spring, a bracket carried by the grip-safety member, a sliding member in said bracket and engaging said grip-safety 50 member, and providing a seat for the lower end of said firing hammer and an abutment for said firing spring, and a trigger-member received in said slot of the slideable controller 55 and engageable with said lower end of the sear member.

9. In a firearm, in combination, a frame of said firearm comprising a grip-stock, a firing member slidably movable to fired position and to firing position, a grip-operable 60 member engageable at one end with said

frame of the firearm and provided at its other end with a frame-end pivotally attached to said grip-stock, and spring means for actuating said firing member, and affording grip-compression of said grip-operable member, and for returning said grip-operable member to engagement with said frame of the firearm after grip-compression. 70

10. In a firearm, in combination, a frame of said firearm comprising a grip-stock, a firing member slidably movable to fired position and to firing position, a grip-operable member engageable at one end with said frame of the firearm and provided at its other end with a frame-end pivotally attached to said grip-stock, to permit removal of the grip-operable member, spring means for actuating said firing member, and affording grip-compression of said grip-operable member, and for returning said grip-operable member to engagement with said frame of the firearm after grip-compression, and means for attaching said spring means to said grip-stock to permit removal of the spring means. 80

11. In a firearm, in combination, a frame of said firearm comprising a grip-stock, a firing member slidably movable to fired position and to firing position and having an extended lower end, a grip-safety member engageable at one end with said frame of the firearm, and provided at its other end with a frame-end insertible in the grip-stock, a pivot-pin slidably insertible in said frame-end for removably attaching said grip-safety member to said grip-stock, a firing spring, a spring plug slidably insertible in said grip-stock and engaging said pivot pin to retain pivot-pin in said frame-end, and for removably attaching said firing spring to said grip-safety member, and a plunger between said firing member and said firing spring and engaging said grip-safety member, for providing a seat for the lower end of the firing member and an abutment for said spring. 95

12. In a firearm, in combination, a firing-pin, reciprocally movable firing-pin actuating means engageable with said firing-pin, means for moving said firing-pin actuating means reciprocally, a firing member slidably movable to fired position and to firing position, and engageable therewith for movement thereby to firing position when said firing-pin actuating means is moved by said means for moving reciprocally, and means for slidably moving said firing member to fired position. 105

13. In a firearm, in combination, a sliding breech action comprising a firing-pin, firing-pin actuating means engageable with said firing pin and movable with said sliding breech action, a firing member slidably movable to fired position and to firing position, and engageable with said firing-pin actuat- 115 120 125 130

- ing means when moved to fired position, and engageable therewith for movement thereby to firing position when said firing-pin actuating means is moved with said sliding breech action, and means for moving said firing member to fired position.
14. In a firearm, in combination, a firing-pin, reciprocally movable firing-pin actuating means engageable with said firing-pin, means for moving said firing-pin actuating means reciprocally, a firing member slidably movable to fired position and to firing position, and engageable at the upper end thereof with said firing-pin actuating means when moved to fired position, and engageable therewith at said upper end for movement thereby to firing position when said firing-pin actuating means is moved reciprocally, and means operatively connected to the lower end of said firing member for slidably moving the firing member to fired position.
15. In a firearm, in combination, a sliding breech action comprising a firing-pin, firing-pin actuating means engageable with said firing-pin and movable with said sliding breech action, a firing member slidably movable to fired position and to firing position, and engageable at the upper end thereof with said firing-pin actuating means when moved to fired position, and engageable therewith at said upper end for movement thereby to firing position when said firing-pin actuator is moved by said means for moving reciprocally, said firing member being provided with a ball-shaped lower end, a spring for slidably moving said firing member to fired position, and a cupped plunger providing a seat for said ball-shaped end of the firing member and an abutment for said spring.
16. In a firearm, in combination, a firing-pin, a reciprocally movable firing-pin actuating member engageable with said firing-pin, means for moving said firing-pin actuating member reciprocally, a firing-member slidably movable to fired position and to firing position, and engageable at the upper end thereof with said firing-pin actuating member when moved to fired position, and engageable therewith at said upper end for movement thereby to firing position when said firing-pin actuating member is moved by said means for moving reciprocally, a spring for slidably moving said firing member to fired position, and means operative between said firing member and said spring providing a seat for the lower end of said firing member and an abutment for said spring.
17. In a firearm in combination, a sliding breech action comprising a firing-pin, a firing-pin actuating member engageable with said firing-pin and movable with said sliding breech-action, a firing member slidably movable to fired position and to firing position, and engageable at the upper end thereof with said firing-pin actuating member and engageable therewith for movement
- when moved to fired position, and engageable therewith at said upper end for movement thereby to firing position when said firing-pin actuating member is moved with said sliding breech action, a spring for slidably moving said firing member to fired position, and means operative between said firing member and said spring providing a seat for the lower end of said firing member and an abutment for said spring.
18. In a firearm, in combination, a firing-pin, a reciprocally movable firing-pin actuator engageable with said firing-pin and provided with an inclined face and an engaging end, means for moving said firing-pin actuator reciprocally, a firing member movable slidably to fired position and to firing position, and provided at the upper end with a roller for engaging said inclined face of the firing-pin actuator and provided with an end-face for engaging said end of said actuator when the firing member is moved to fired position, and for engaging said inclined face of said actuator for movement thereby to firing position when said firing-pin actuator is moved by said means for moving reciprocally, said firing member being provided with a ball-shaped lower end, a spring for slidably moving said firing member to fired position, and a cupped plunger providing a seat for said ball-shaped end of the firing member and an abutment for said spring.
19. In a firearm, in combination, a sliding breech action comprising a firing-pin, a firing-pin actuator engageable with said firing-pin and provided with an inclined face and an engaging end and movable with said sliding breech action, a firing member slidably movable to fired position and to firing position and provided at the upper end with a roller for engaging said inclined face of the firing-pin actuator and provided with an end-face for engaging said end of said actuator when the firing member is moved to fired position and for engaging said inclined face and end of said actuator for movement thereby to firing position when said firing-pin actuator is moved with said sliding breech action, said firing member being provided with a ball-shaped lower end, a spring for slidably moving said firing member to fired position, and a cupped plunger providing a seat for said ball-shaped end of the firing member and an abutment for said spring.
20. In a firearm, in combination, a firing-pin, reciprocally movable firing-pin actuating means engageable with said firing-pin, means for moving said firing-pin actuating means reciprocally, a firing member slidably movable to fired position and to firing position and engageable with said firing-pin actuating means when moved to fired position, and engageable therewith for movement

thereby to firing position when said firing-pin actuating means is moved by said means for moving reciprocally, sear means engageable with said firing member to lock the firing member in firing position, and means for slidably moving said firing member to fired position.

21. In a firearm, in combination, a sliding breech action comprising a firing-pin, firing-pin actuating means engageable with said firing-pin, and movable with said sliding breech action, a firing member slidably movable to fired position and to firing position and engageable with said firing-pin actuating means when moved to fired position, and engageable therewith for movement thereby to firing position when said firing-pin actuating means is moved with said sliding breech action, and sear means engageable with said firing member to lock the firing member in firing position.

22. In a firearm, in combination, a firing-pin, reciprocally movable firing-pin actuating means engageable with said firing-pin, means for moving said firing-pin actuating means reciprocally, a firing member slidably movable to fired position and to firing position and engageable with said firing-pin actuating means when moved to fired position, and engageable therewith for movement thereby to firing position when said firing-pin actuating means is moved by said means for moving reciprocally, sear means engageable with said firing member, slidable means movable in a direction to lock said sear means and firing member in firing position, means engaging said slidable means and engaging said firing member for resisting movement of the firing member from firing position to fired position, and for moving said slidable means in a direction reverse to said first mentioned direction when said firing member is moved to fired position, and means for slidably moving said firing member to fired position.

23. In a firearm, in combination, a sliding breech action comprising a firing-pin, firing-pin actuating means engageable with said firing-pin and movable with said sliding breech action, a firing member slidably movable to fired position and to firing position, and engageable with said firing-pin actuating means when moved to fired position, and engageable therewith for movement thereby to firing position when said firing-pin actuating means is moved by said sliding breech action, sear means engageable with said firing member, slidable means engageable with said sliding breech action and movable in a direction to lock said sliding breech action, and lock said sear means and firing member in firing position, means engaging said slid able means and engaging said firing member for resisting movement of the firing member from firing position to fired position, and for

moving said slidable means in a direction reverse to the first mentioned direction when said firing member is moved to fired position, and means for slidably moving said firing member to fired position.

24. In a firearm, in combination, a firing-pin, a reciprocally movable firing-pin actuator engageable with said firing-pin, and provided with an inclined face and an engaging end, means for moving said firing-pin actuator reciprocally, a firing member slidably movable to fired position and to firing position, and provided at its upper end with a roller and an end-face for engaging said inclined face and end of the firing-pin actuator when moved to fired position, and for engaging said inclined face and end of the firing-pin actuator for movement by said actuator to firing position when said actuator is moved by said means for moving reciprocally, said firing member being provided with a cock-notch, and provided with a ball-shaped lower end, a sear member provided with a lock-notch for engaging said cock-notch, and provided with an extending end, a slid able controller movable in a direction to lock said sear member and firing member in firing position, a resisting and retracting member engaging said slid able controller and engaging said firing member for resisting movement of the firing member to fired position, and for moving said slid able controller in a direction reverse to the first mentioned direction when said firing member is moved to fired position, a spring for moving said firing member to fired position, a cupped plunger operatively located between said firing member and said spring providing a seat for said ball-shaped end of the firing member and an abutment for said spring, and a trigger member engageable with said extending end of the sear member.

25. In a firearm, in combination, a sliding breech action comprising a firing-pin, a firing-pin actuator engageable with said firing-pin and movable with said sliding breech action, and provided with an inclined face and an engaging end, a firing member slidably movable to fired position and to firing position, and provided at its upper end with a roller and an end-face for engaging said inclined face and end of the firing-pin actuator when moved to fired position, and for engaging said inclined face and end of the firing-pin actuator for movement by said actuator to firing position when said actuator is moved with said sliding breech action, said firing-member being provided with a cock-notch, and provided with a ball-shaped lower end, a sear member provided with a lock-notch for engaging said cock-notch and provided with an extending end, a slid able controller movable in a direction to lock said sliding breech action, and lock said sear member and firing member in firing position,

a resisting and retracting member engaging said slidable controller and engaging said firing member for moving said slidable controller in a direction reverse to the first mentioned direction when said firing member is moved to fired position, a spring for moving said firing member to fired position, a cupped plunger operatively located between said firing member and said spring providing a seat for said ball-shaped end of the 10 firing member and an abutment for said spring, and a trigger member engageable with said extending end of the sear member.

JOHN D. PEDERSEN.
